UNITED STATES PATENT OFFICE.

ABEL E. CHERNACK, OF PROVIDENCE, RHODE ISLAND.

LOOM.

1,300,121.

Specification of Letters Patent.

Patented Apr. 8, 1919.

Application filed March 25, 1914. Serial No. 827,151.

To all whom it may concern:

Be it known that I, ABEL E. CHERNACK, a subject of the Emperor of Russia, and a resident of the city of Providence, county 5 of Providence, and State of Rhode Island, have invented certain new and useful Improvements in Looms, of which the following is a specification.

My invention relates more particularly to 0 the construction of looms of that class in which a large shuttle containing a large bobbin of weft thread, and therefore of considerable weight, is driven positively through the shed of any desired width. My present 5 improvements have reference especially to the construction and operation of the reed.

In the accompanying drawings,

Figure 1 is a side elevation of a loom embodying my present invention;

Fig. 2 is a corresponding longitudinal vertical section;

Fig. 3 is a sectional view, drawn to a larger scale, showing the shuttle motion and reed construction;

Fig. 4 is a diagram to the same scale, showing the reed blades in closed position;

Fig. 5 is a side elevation of the reed blades drawn to a still larger scale;

Fig. 6 shows a series of sectional views 10 through these two blades along the several lines indicated in Fig. 5;

Fig. 7 shows in front and rear edge views and in side view one of the upper reed blades;

Fig. 8 shows similar views of one of the lower blades;

Fig. 9 is a diagram illustrating the differential motion of the mechanism for operating the batten.

In the present instance I have shown my 10 invention as applied to a loom in which the heddles are vertical and the warps pass through the loom in a horizontal direction.

The frame F of the machine, which may 15 be of any suitable construction, supports at one end a warp beam B and at the other end a cloth beam B¹, Figs. 1 and 2. The threads from the warp beam B pass under

two stationary guide beams 35 and 36 and over an intermediate vertically-reciprocating beam 34, Fig. 2. This beam 34 slides at its opposite ends in vertical guide ways f, f, in the side frames of the machine, and rests by gravity by means of antifriction rollers 33 upon two cams 32 fixed to the rotary crank shaft 18, toward the opposite ends of that shaft. By this means the beam 34 rises and falls in correspondence with the shed, and the tension for the warp beams is kept uniform.

The warp threads after leaving these guide beams pass through heddles H, which may be supported and operated in any suitable way. In Fig. 2, I have shown them as supported by straps passing over pulleys 51 on an overhead shaft 52 in bearings on a pair of cross-beams 53. The lower ends of the respective heddles are connected to treadles 37 and 38, which are pivoted to the frame and are acted on by cams 39 and 40 secured to the cross shaft 20.

After leaving the heddles the warps pass the shuttle, which is traversed through the warp sheds on fixed guide-ways by driving means in accordance with the invention forming the subject of my Patent 1,117,791, November 17, 1914, as more fully explained 75 hereinafter.

The warps then pass through the beating-up reed, which is of the two-part type, the two parts opening for the laying of the weft thread in front of the reed and closing for the beating-up motion, and the shed forming. The cloth passes over suitable rollers b, b¹ to the cloth beam B¹.

For the sake of simplicity I have omitted the shuttle from Figs. 1 and 2.

The shuttle S, which is preferably shaped like an ordinary shuttle, is mounted to be traversed to and fro in a stationary race-way, consisting of upper and lower fixed guide bars 17 and 18 above and below the warps. The inner faces of these guide bars have comb-like teeth of sufficient depth to permit the warp threads, when the shed is 95 formed, to pass into the spaces between the

teeth out of the way of the passing shuttle, Fig. 3. These two guide bars 17 and 18 are preferably V-shaped on their guide faces to receive the correspondingly grooved peripheries of supporting and guiding rollers at the upper and lower edges of the shuttle frame.

The bobbin N is contained within the hollow portion of the shuttle, which has a projecting finger 48 with a guide eye at its outer end to carry the weft thread from the shuttle between the separated parts of the reed, as shown in Fig. 3.

The wheel 6 and its shaft 20 may be driven from the main shaft 1 through the medium of gears 2, 3, and 4, Fig. 1. This last mentioned gear 4 may mesh with gear 5 to drive the crank shaft 19.

This crank shaft 19, through the medium of connecting rods 23 and 24 and radius rods 22 on the cross shaft 21, imparts a differential reciprocating motion to the batten or lay 25, which is pivoted at 26 to the frame (Fig. 2) and carries at its upper end the divided reed. This divided reed is preferably built up from a series of blades 60 and 61 which may be alike for both the upper and lower halves of the reed. Each blade comprises a thickened base or heel *m* and a thin body *n* having the outline of a right angled triangle. The outer points *p* of these triangular outlines are thinned to a sharp edge, as seen in Figs. 5 to 8, and the lower blades which are the beating-up blades are also somewhat thinned at their beating-up edges *o*, but thickened toward their outer edge *q*. The reason for thinning the beating-up edges *o* is that if left thick, they would be liable to produce a "reedy" effect in the woven cloth. The upper blades are of like construction.

The blades of the lower set 60 are fitted together side by side in a transverse groove in the upper side of the bar 25' of the batten 25 and held in place by a detachable plate 64, Fig. 3. The blades of the upper set 61 are similarly secured in reverse position in the lower side of a cross bar 29, which by arms 28 is pivoted at 27 to the forward side of the upper end of the batten 25. Anti-friction rollers 30 on the arms 28 run in stationary cam grooves 31 in the side frames, Figs. 2 and 3. These cam grooves are such as to move the upper and lower reed blades 55 apart, when the batten is moved up to the shuttle race, as seen in Fig. 3, to permit the weft to be laid in front of the reed, but when the batten is moved in the opposite direction toward the cloth, the upper and lower blades will approach each other, as indicated in Fig. 2, and be closely adjacent at the beating-up point, as seen in Fig. 4. The

several blades of the upper set are always in line with the corresponding blades of the lower set, and the opening and closing movements of the two parts of the reed will so far correspond with the shed-forming movements of the warps that the warps will always be confined within their proper places between the blades, and the upper line of warps will pass to the lower position and vice versa only when the blades overlap each other, as in the position shown in Fig. 2, for example. The overlapping of the thinned points *p* of one set, as seen in the sectional view, Fig. 6, not only serves to protect those points, but also helps to keep the warps in their proper places between blades or dents in forming the warp sheds.

The differential movement imparted to the batten from the crank shaft 19 will be best understood by reference to the diagrams, Fig. 9, in connection with Fig. 2. The angle of the radius rods 22 is arranged with such relation to the angle of the crank of the shaft 19 that when the crank makes a quarter revolution in passing from the position *x*, Fig. 9, to the position *y* in that figure, the batten 25 will have been moved only the angular distance *X*, but in the next quarter revolution of the crank from *y* to *z*, Fig. 9, the batten 25 will be moved through the angle *Y*, say twice the angle *X*. By this differential movement I am able to give a relatively powerful blow to the batten for beating-up,—a feature of importance especially in the weaving of heavy fabrics. On the other hand, the movement of the batten is relatively slow while the shuttle is passing through the warps.

I claim as my invention:—

1. A loom, having needles and a shuttle, with a reed composed of two combs, an oscillating batten carrying the weft-bearing portion of the reed, arms carrying the other portion of the reed and pivoted to the batten, and fixed cams to act on said arms to open and close the two parts of the reed as the batten is moved backward and forward.

2. A loom, having a two-part reed, each part composed of blades with bodies of triangular outline, the points being thinned, the two sets of blades being placed to bring the thinned points in one set adjacent to the thickened edges of the other set.

3. A loom, having a two-part reed, each part composed of blades with thickened bases and thin bodies, having points thinned to a sharp edge, for the purpose described.

4. A loom, having a two-part reed, a batten carrying the two parts of the reed, one part being secured in the batten and the other pivoted thereto in combination with means to reciprocate the batten and a fixed

cam to open and close the two parts of the reed as the batten is reciprocated.

5. A loom, having a two-part reed, a batten carrying the two parts of the reed, movable with reference to each other as the batten reciprocates, each part of the reed being composed of sets of blades, all alike, and each comprising a thickened base and a thinned body of substantially triangular out-

line, the blades of one set being placed in 10 reversed relation to the other set.

In testimony whereof I have signed my name to this specification, in the presence of two subscribing witnesses.

ABEL E. CHERNACK.
